NECKTIE CONTAINER AND SUPPORTING RACK

Harry W. Hibbs, Princeville, Ill.

Application April 5, 1948, Serial No. 19,117

16 Claims. (Cl. 312—276)

1

The invention relates to a necktie container and supporting rack.

An object of the present invention is to provide a simple, practical and comparatively inexpensive necktie container and supporting rack of strong, durable and highly ornamental construction, adapted to support a large number of neckties compactly in a comparatively small space, free from dust and wrinkles.

Another object of the invention is to provide a necktie cabinet and supporting rack adapted for use by individuals as well as for display purposes in the sale of neckwear and equipped with a cabinet having a transparent body portion so that its contents may be readily viewed from the exterior.

A further object of the invention is to provide a necktie container and supporting rack provided with a plurality of tie holders each adapted to hold a plurality of neckties and capable of being withdrawn from the cabinet or container, either singly or all together, so as to afford ready access to the contained neckties and capable, when returned to the cabinet, of compressing the neckties and removing therefrom any wrinkles incident to the use of a necktie by the wearer so that the device will always provide the wearer with a clean, neat necktie.

It is also an object of the invention to provide a necktie container and supporting rack of a portable character adapted to be conveniently carried when traveling and capable also of being readily mounted in fixed position on a wall or placed upon a supporting surface and when opened or closed will always support the contained neckties in a vertical hanging position without any danger of wrinkling its contents.

Another object of the invention is to provide a necktie container and supporting rack provided with a door hinged at the top and adapted in opening to swing upwardly to a horizontal position and held in such position by means which also constitutes a portion of a track or guideway for supporting the necktie holders when the same are withdrawn from the body portion of the cabinet or container.

It is also an object of the invention to provide a simple and effective locking device for securing the door in its open position and readily adjustable into locking engagement with keeper means when the door is raised to its horizontal open position.

With these and other objects in view, the invention consists in the construction and novel combination and arrangement of parts herein-after fully described, illustrated in the accom-

2

panying drawings and pointed out in the claims hereto appended, it being understood that various changes in the form, proportions, and minor details of construction, within the scope of the claims, may be resorted to without departing from the spirit or sacrificing any of the advantages of the invention.

In the drawings:

Figure 1 is a vertical sectional view of the necktie container and supporting rack constructed in accordance with this invention, the supporting rack being shown in elevation and the cabinet or container being shown closed;

Figure 2 is a transverse sectional view taken substantially on the line 2—2 of Figure 1;

Figure 3 is a top plan view of the necktie container and supporting rack, the parts being arranged as illustrated in Figure 1;

Figure 4 is a vertical longitudinal sectional view, the container being open and showing several of the necktie holders being withdrawn from the container;

Figure 5 is a plan view of the left hand portion of Figure 4 and showing the locking device in its locking position;

Figure 6 is a front elevation of the necktie container;

Figure 7 is a transverse sectional view taken substantially on the line 7—7 of Figure 1;

Figure 8 is a detail sectional view taken on the line 8—8 of Figure 4 and showing the locking device in its locking position;

Figure 9 is a detail horizontal sectional view taken on the line 9—9 of Figure 6 and showing the locking device in its sliding position;

Figure 10 is a detail perspective view of one of the necktie holders;

Figure 11 is an exploded detail view of the locking device;

Figure 12 is a sectional view of the same, taken on the line 12—12 of Figure 11.

In the accompanying drawings, in which is illustrated the preferred embodiment of the invention, the container or cabinet preferably consists of a transparent body portion 1 constructed of plastic or any other suitable material and composed of an end wall 2, vertical sides 3, an arched top 4 and a horizontal bottom 5 which may conveniently be formed in a single-piece or unitary structure. The end wall 2 constitutes the back of the container which is provided at the front with a door 6, hinged at the top to the top of the body portion 1 by a suitable hinge 7 and adapted to be swung upwardly from the vertical closed position illustrated in Figure 1

of the drawings to the substantially horizontal top or open position illustrated in Figure 4 of the drawings to afford access to the contents of the container.

The container is provided with a plurality of necktie holders 8 slidable along and removable from a top track composed of a stationary track section 9 and a hinged track section 10 connected at one end to the stationary track section 9 by a suitable hinge 11 and slidably connected at its other end with the door by a locking device 12 which maintains the hinged door in its elevated horizontal position when the door is opened.

The track sections are flanged and substantially inverted T-shape in cross section and the 15 stationary track section 9 is suitably secured to the top 4 of the body 1 of the container. The hinge 11 has its leaves secured to the flanges of the track sections and is located at the lower face of the stationary track section and also that of the hinged track section when the latter is in the horizontal position.

The hinged door, which may be constructed of any suitable material, is provided at its upper portion with a longitudinal opening 13 to receive the web portion of the hinged track section and it is also provided with a slot 14 in which the locking device 12 slides in the opening and closing movements of the door. In the drawings the slot is formed in the plate 15 which bridges the lower portion of the opening 13, but any other suitable construction may, of course, be provided for the accommodation of the locking device which slidably connects the hinged track section with the door and which cooperates with the hinged track section to provide means for holding the door in its open elevated horizontal position.

The locking device 12 comprises a bolt 16 and a pivoted catch 17 mounted on the bolt 16 adjacent the head 18 and adapted to be turned to a position transversely of the slot 14 to engage a transverse recess 19 extending from opposite sides of the slot 14. The walls of the slot 14 are recesses longitudinally at 20 to receive the catch 17 when the catch is turned from a position transversely of the slot 14 to a position longitudinally thereof, and the longitudinal recesses form a guide for the catch in the sliding movement of the locking device when the door is opened, or when it is closed. The bolt is provided at its threaded end with a nut 21 and a coil spring 22 is arranged on the bolt and interposed between the nut and the hinged section of the track through which the bolt passes. The spring 22 yieldably maintains the catch in engagement with either the longitudinal recess 20 at opposite sides of the slot 14, or in its position transversely of the slot 14 when it is in engagement with the transverse recess 19. The catch, which is substantially U-shape, as clearly illustrated in Figure 12 of the drawings, is composed of two sides and a transverse connecting portion which is provided with an opening 23 for the reception of the bolt 16. The sides of the catch are adapted to be readily grasped for drawing the bolt outwardly to permit the turning of the catch to arrange the locking device for sliding in the slot 14 or for holding the locking device against sliding movement. When the door is closed the spring 22 maintains the catch in frictional engagement with the door for holding the door in its closed position.

When the door is in its open position the hinged track sections form a continuous track and the laterally extending flanges of the track

sections are adapted to be engaged by lugs 24 extending inwardly from opposite sides of the hanger member or portion 25 of the tie holders 8, which are provided with arms 26 extending horizontally from opposite sides of the hanger portion 25. The hanger portion 25 is centrally arranged and extends upwardly from the arms 26 and is provided with an opening 27 forming in the hanger a substantially U-shaped track-receiving and track-engaging portion which is provided at opposite sides with the said lugs 24.

Any desired number of tie holders may, of course, be employed and the tie holder at the inner end of the set is provided with a horizontal operating rod 28 which extends outwardly through the openings 27 and is adapted to be readily grasped for enabling the entire set of tie holders to be simultaneously withdrawn from the body of the container. The tie holders may be individually or collectively withdrawn from the body of the container and they may also be individually and collectively removed from the track by sliding them off the hinged track section at the end where the same is slidably connected with the door.

It will be seen that the individually slidable tie holders may be compactly arranged and will enable a large number of neckties to be supported within a comparatively small space and also will enable the neckties to be pressed together when the holders are moved into the body of the container. The compressing of the ties within the container will remove wrinkles from the worn necktie and a fresh, neat, unwrinkled necktie may be readily obtained at any time. While the device is designed for the use of individuals, it may be advantageously employed for displaying and protecting neckties for sale. The neckties, when arranged on the tie holders, always remain in the depending vertical position, whether the tie holders are located within the container or are slid outwardly therefrom and supported on the track extension formed by the hinged section, which performs the dual function of supporting the necktie holders and of cooperating with the locking device for maintaining the door in its elevated open position.

An suitable means may be provided for enabling the necktie container and supporting rack to be mounted on the wall; it may be arranged upon any supporting surface and may be conveniently carried while traveling.

While the device is especially designed for holding neckties, it may be advantageously employed for protecting and supporting various other articles.

I claim:

1. A device of the class described including a container having a door hinged at the top, a hanger supporting track having a hinged section slidably connected with the door, and a locking device connected to the hinged track section and with the door and slidably on one of said parts and having means arranged to engage the same when the door is opened whereby the door is locked in its open position and the hinged track section is adapted to support the door in an elevated open position.

2. A device of the class described including a container having a door hinged at the top, a hanger supporting track having a hinged section slidably connected with the door, and a locking device connected to the hinged track section and slidably mounted on the door and engageable

with the same for locking the door in an open elevated position.

3. A device of the class described including a container having a door hinged at the top, a hanger supporting track having a hinged section slidably connected with the door, and a locking device connected to the hinged track section and slidably mounted on the door and provided with a catch movable into and out of engagement with the door and engageable with the same for locking the door in an open elevated position and for maintaining the hinged track section in a horizontal supporting position.

4. A device of the class described including a container having a door hinged at the top, a hanger supporting track having a hinged section slidable on the door and a locking device also slidably on the door and comprising a bolt secured to the hinged track section and extending through a slot in the door, and a catch pivotally mounted on the bolt and engageable with the door exteriorly thereof for maintaining the hinged track section in a horizontal position and for maintaining the door in its open position.

5. A device of the class described including a container having a door hinged at the top and adapted to be swung upwardly to open the container, said door being provided with a slot, a track having a hinged section, and a locking device having a bolt extending through the slot of the door and through the hinged track section and slidably connecting the same with the door, and a pivoted catch mounted on the bolt and arranged exteriorly of the door for engaging the same to hold the door in its open position and maintain the hinged track section in a horizontal position and yieldable means carried by the bolt and maintaining the catch yieldably and frictionally in engagement with the door.

6. A device of the class described including a container having a door hinged at the top and adapted to be swung upwardly to open the container, said door being provided with a slot, a track having a hinged section, and a locking device having a bolt extending through the slot of the door and through the hinged track section and slidably connecting the same with the door, and a pivoted catch mounted on the bolt and arranged exteriorly of the door for engaging the same to hold the door in its open position and maintain the hinged track section in a horizontal position and yieldable means carried by the bolt and maintaining the catch yieldably and frictionally in engagement with the door, said door being also provided with keeper means for effecting a positive interlocking of the catch and the door when the latter is open.

7. A device of the class described including a container body open at the front, a door hinged to the body at the top thereof and arranged to open upwardly to elevated approximately horizontal position, a stationary track section located within said container body, a movable track section hinged at one end to the stationary track section and having its other end slidable on the door, said track sections forming a continuous track when the door is open, and a locking device for rigidly connecting the hinged section with the door for maintaining the hinged section in a horizontal position and for securing the door in an open position.

8. A device of the class described including a container body open at the front, a door hinged to the body at the top thereof and arranged to open upwardly to elevated approximately hori-

zontal position, a stationary track section located within said container body, a movable track section hinged at one end to the stationary track section and having its other end slidable on the door, said track sections forming a continuous track when the door is open, and a locking device slidable on the door and connected with the hinged track section and provided with a catch movable into and out of engagement with the door and engageable with the door for holding the same in its open position and for maintaining the hinged track section in a horizontal position.

9. A device of the class described including a container body provided with a door hinged to the body at the top thereof and arranged to open upwardly to an elevated approximately horizontal position, said door being provided with a slot and having a transverse recess extending laterally from opposite sides of the slot, a stationary track section located within said container body, a movable track section hinged at one end to the stationary track section and having its other end slidable on the door, and a locking device secured to the hinged track section and extending through the slot of the door and provided with a pivotally mounted catch adapted to be arranged transversely of the slot and engageable with the transverse recess thereof for locking the door in an elevated open position and for maintaining the hinged track section in a horizontal position in alignment with the stationary track section.

10. A device of the class described including a container body having a door hinged at the top and movable upwardly to an open position, a flanged track having a hinged track section slidably connected at one end with the door and adapted to be swung upwardly to a horizontal position when the door is opened, said track sections being flanged, and individual holders slidably along the track sections and having means for engaging the flanges thereof.

11. A device of the class described including a container body having a door hinged at the top and movable upwardly to an open position, a flanged track having a hinged track section slidably connected at one end with the door and adapted to be swung upwardly to a horizontal position when the door is opened, said track sections being flanged at opposite sides thereof, and individual holders provided with hanger portions having openings receiving the track sections and provided with inwardly projecting lugs engaging the flanges of the track sections, said lugs extending inwardly over the flanges and having their terminals arranged closely adjacent the track and adapted to prevent lateral separation of the individual holders from the track and permit removal of the holders only at the end of the track.

12. A device of the class described including a container body having a door hinged at the top and movable upwardly to an open position, a flanged track having a hinged track section slidably connected at one end with the door and adapted to be swung upwardly to a horizontal position when the door is opened, said track sections being flanged at opposite sides thereof, and a set of individual holders having hanger portions provided with openings slidable along the track sections and having means for engaging the flanges thereof, and an operating rod connected with the innermost holder of the set and extending through the openings in the other

holders and adapted to permit the entire set of holders to be moved simultaneously along the track sections.

13. A device of the class described including a container provided at the front with a door, a horizontal track mounted within the container and having longitudinal flanges extending laterally from opposite sides of the track and individual holders comprising a central hanger portion provided with an opening receiving the track and having lugs extending inwardly from opposite sides of said opening and slidable upon said flanges and extending inwardly to points closely adjacent the track to prevent lateral separation of the central hanger portion from the track and permit removal only at the end of the track, and horizontal article-supporting arms extending from opposite sides of the central hanger portion.

14. A device of the class described including a container body open at the front, a door hinged to the container at the front thereof, a track comprising a stationary track section located within the container and extending from the back thereof to a point adjacent the door, and a movable track section hinged at one end to the stationary track section, means for raising and lowering the hinged track section when the door is opened and closed, including a slidable connection between the door and the hinged section, and a catch arranged to engage one of said parts for locking the hinged section in its

raised position, and individual holders slidable along the track.

15. A device of the class described including a container having a door hinged at the top, a hanger-supporting track having a hinged section located at the front of the container, and a locking device for securing the hinged section to the door when the door is opened and the hinged section is raised to a horizontal position, whereby said parts are maintained in said positions.

16. A device of the class described including a container having a hinged door, a track comprising a fixed section and a hinged section located adjacent the door and arranged to hang downwardly from the fixed section when the door is closed, and means operatively connected with the door and the hinged track section for raising and lowering the hinged track section when the door is opened and closed.
